UNITED STATES PATENT OFFICE.

WILLIAM BLANCHARD, OF HOUSTON, TEXAS.

SUBMERGED BRIDGE.

Application filed April 30, 1925. Serial No. 27,014.

This invention relates to a submerged bridge, especially designed for crossing wide streams, or other bodies of water, where the soil formation is such as to make it very difficult to secure a permanent foundation. Typical examples of such conditions are found in the lower part of the Mississippi basin.

The present invention has been devised 10 as an improvement over the construction shown in my former Patent No. 947,791, issued February 22, 1910, and its principal object is to provide improved means for supporting the intermediate spans of the bridge, and improved means for anchoring the same, so that they will be more stable and dependable, especially during the rapid flow of the river occasioned by high water.

20 The invention consists further in various details of construction, the advantages of which will be more particularly explained in connection with the accompanying drawings, illustrating one embodiment of the invention.

In the drawings:

Figure 1 is a side elevation of the invention with the adjoining embankments and river bed shown in section.

30 Figure 2 is a plan view of the invention.

Figure 3 is a transverse section thereof taken substantially on the line 3—3 of Figure 1.

Figure 4 is a longitudinal section through one of the intermediate foundations, and showing also a portion of the viaduct and one of the end piers.

In its present embodiment, the invention is shown in connection with a bridge having 40 a central section 5, which is of such length as to extend approximately from one bank of the river to the other, and the extremities of this central section are united with shore sections 6, which are slightly inclined upwardly from the river bank to emerge upon the surface of the land at points more or less remote from the river, the river being shown in the present instance as confined between levees 7. Close 50 to each bank of the river is a pier 8 for supporting the end of the central section 5. This pier may be readily constructed by the use of a cofferdam extending outwardly from the bank of the river, the section 5 being built on the edge of the bank and subsequently launched, like a boat, and

60 floated into place, removable bulk heads being provided in the ends of the section, which may be opened to admit water when the section has been floated into proper position. The section 5 is of greater length than the distance between the two piers 8, so that it projects beyond the same, and is united to the respective shore sections 6 at the dotted lines 9, Figure 1. The end portions of the section 5 are formed with saddles 10, which rest on the piers 8.

65 The piers 8 are constructed after the cofferdams are built, and each pier is preferably constructed in the manner shown in the above mentioned patent. That is, each pier is formed of a number of hollow metallic cylinders 11, which are driven into the river bottom to the desired depth, and the mud or earth is then removed from the interior of the cylinders and the latter filled with concrete. These cylinders are tied together in any suitable manner, and concrete is molded around them to form piers of any desired dimensions. Embedded in the concrete in the upper ends of the cylinders are 70 tie rods 12, having anchoring devices 13, and these tie rods extend upwardly through the wall of the section 5, which is thereby secured to the pier. The piers not only hold 75 the bridge against lateral displacement, but serve as anchoring means to hold down the bridge against any tendency to rise by reason of its buoyancy. In constructing the 80 land sections 6 of the bridge, the levees, or banks of the river, are excavated behind the cofferdam, and after a foundation has been laid, consisting of piles 14 that support a bed of concrete 15, the sections 6 of the bridge are built up. When these two sections 85 are completed, and the section 5 assembled between them, the extremities of the sections are united at the dotted lines 9. After being thus united, the shore ends of the bridge are enveloped in a casing of concrete 16, which extends laterally both up 90 and down the stream and shoreward from the piers 8, and provides a practically indestructible anchoring means for the ends 95 of the bridge. The casing 16 has oppositely sloping top surfaces and oppositely curved sides, so as to form little obstruction to the flow of water. After this casing has been 100 constructed, the levees or banks of the river are restored, and if desired, a retaining wall 17 may be built on the land side of each 105 levee for securing greater security.

Each section of the bridge is constructed in the form of a metal tube, composed of plates 18 riveted together about a skeleton framework, consisting of arcuate ribs 19. A vertically disposed bulk head 20 extends longitudinally of the bridge and centrally thereof for providing separate passageways for trains or other vehicles, the bulk head having man holes 21, so that track hands can conveniently pass from one side to the other without having to go to the terminals of the bridge. The bulk head projects downwardly below the tubular viaduct formed by the plates 18, and constitutes a keel extending the full length of the bridge, and braced by arcuate plates 22, as shown in Figure 3. After the viaduct has been constructed, the same is covered with a protective coating 23 of concrete, which entirely houses the metal parts of the structure and protects the same from corrosion. A roadbed 24 of concrete or other suitable material is laid inside of the tubular viaduct.

The construction of the viaduct and the approaches is substantially similar to the construction disclosed in my former patent. The means for supporting the intermediate portions of the bridge, however, embody entirely different features, involving new principles of bridge construction. Each of these intermediate foundations comprises a comparatively large barge or scow 25, made of reinforced concrete forming a single closed compartment which is substantially watertight. The barge is formed centrally with an upwardly extending hollow column 26, the interior of which forms a well, which extends entirely through the barge. A structural steel frame or superstructure 27 is secured to the barge and surrounds the column 26 forming a support for the saddle 28, which is secured to the bridge section 5 where it is desired to provide an intermediate support therefor. A metallic cylinder 29 is mounted within the tower 26, and is provided with an outwardly extending base 30, adapted to engage the underside of the barge 25, and to be held against the same by the pressure of the water while the structure is being floated into position.

After the barge and tower have been constructed on shore, they are launched into the water and floated into proper position. The seacocks of the barge are then opened, and the foundation sinks to the bottom of the river. The bridge section 5 is provided, in its bottom, with tubes 31, which may be closed while the barge is being floated into position, and which may then be opened to permit the cylinders 29 to be filled with ballast. The barge 25 is of large dimensions, not less than 150 feet long and 100 feet wide, so that it will lie upon the river bed without settling. The central cylinder 29, after being filled with ballast will gradually settle downward-

ly into the bed of the river, as shown in dotted lines in Figure 4, and will in time reach a solid resting place. Ballast is added from time to time through tubes 31 as the same becomes necessary.

By constructing the foundations in the manner indicated, it is possible to construct a bridge across a river or other body of water, where the soil is of such a nature as to preclude the construction of a foundation in the usual manner. There is very little hazard or risk in the construction of a bridge in this manner. It is proposed to locate it deep enough so as not to interfere with navigation. The cost of maintenance is also very small. Furthermore, since the main section of the bridge and the intermediate foundations for supporting it can be built upon the land and launched and floated into place, it is obvious that less labor and time are required in its construction than in constructing aerial bridges.

While I have shown and described what is considered, at the present time, the preferred embodiment of the invention, it is apparent that various modifications may be made therein without any material departure from the salient features thereof. It is my intention, therefore, to include all such modifications within the scope of the appended claims.

What is claimed is:

1. In a submerged bridge, the combination of a tubular section enclosing a road-bed, a submerged barge resting on the bottom of the waterway, a superstructure extending upwardly from the barge and forming an intermediate support for said section, and a vertically disposed cylinder within said superstructure and extending through the barge and adapted to contain ballast, the base of said cylinder being extended laterally beneath the bottom of the barge.

2. In a submerged bridge, the combination of a tubular section enclosing a road-bed, a submerged barge resting on the bottom of the waterway, a superstructure secured to and extending upwardly from the barge and forming an intermediate support for said section, and a vertically disposed cylinder located centrally of said superstructure and extending substantially from top to bottom thereof and through the bottom of the barge and provided with a laterally extended base engageable with the bottom of the barge, said cylinder being adapted to contain ballast and being slidably downwardly through the barge to form an anchor therefor.

3. In a submerged bridge, the combination of a tubular section enclosing a road-bed, a submerged barge resting on the bottom of the waterway, a superstructure extending upwardly from the barge and forming an intermediate support for said section, a cylinder disposed vertically within said super-

structure and extending through said barge, said cylinder being adapted to contain ballast, the base of said cylinder being extended laterally beneath the bottom of the barge 5 and a passageway leading from the interior of said tubular section to the interior of the cylinder for introducing ballast into said cylinder.

4. In a submerged bridge, the combination 10 of a tubular section enclosing a road-bed, a submerged barge resting on the bottom of the waterway, a superstructure extending upwardly from the barge and forming an intermediate support for said section, a cylinder disposed vertically within the superstructure and extending through the bottom of the barge, the base of said cylinder being extended laterally beneath the bottom of the barge, said cylinder being slidable downwardly 20 to form an anchor for the barge, and a passageway leading from the interior of said tubular section to the interior of the cylinder for introducing ballast into the interior of said cylinder.

25 5. In a submerged bridge, the combination of a tubular section enclosing a road-bed, a submerged barge formed of reinforced concrete and resting on the bottom of the waterway, a skeleton superstructure secured to and extending upwardly from the support 30 and forming an intermediate support for said section, said barge having a hollow column integral therewith and extending upwardly within the superstructure and also extending downwardly through the barge to form a well, and a cylinder within the well adapted to contain ballast and having an extended base engageable with the bottom of the barge.

40 6. In a submerged bridge, the combination 45 of a tubular section enclosing a road-bed, a submerged barge resting on the bottom of the waterway, a superstructure extending upwardly from the barge and forming an intermediate support for said section, said barge having a well formed centrally thereof, the wall of said well extending upwardly within the superstructure, and a cylinder 50 within the well adapted to contain ballast and having an extended base engageable with the bottom of the barge, said cylinder being slidable downwardly under the weight

of the ballast to form an anchor for the barge.

7. In a submerged bridge, the combination 55 of a tubular viaduct section, a submerged barge of reinforced concrete resting on the bottom of the waterway, a superstructure secured to and extending upwardly from the barge and forming an intermediate support for said section, said barge having a well formed centrally therethrough, the wall of said well extending upwardly within the superstructure, a cylinder within the well and having an extended base engageable 60 with the bottom of the barge, and a passageway leading from the interior of the viaduct to the interior of the cylinder for introducing ballast into said cylinder.

8. In a submerged barge, the combination 70 of a tubular viaduct, a submerged barge resting on the bottom of the waterway, a superstructure secured to and extending upwardly from the barge and forming an intermediate support for said viaduct, said barge having a well formed centrally therethrough, the wall of said well extending upwardly within the superstructure, a cylinder within the well and having an extended base engageable 75 with the bottom of the barge, said cylinder being slidable downwardly to form an anchor for the barge, and a passageway leading from the interior of the viaduct to the interior of the cylinder for introducing ballast into said cylinder.

9. A construction for supporting the intermediate portion of a submerged bridge, said construction comprising a barge with a superstructure secured to and extending upwardly therefrom, said barge having a substantially watertight compartment sufficiently large so that it may be floated and subsequently sunk in position for said structure to support the bridge, and a cylinder 90 extending vertically through the barge and substantially to the top of said superstructure and adapted to receive ballast, said cylinder having an extended base engageable with the bottom of the barge while the barge and cylinder are being placed in position.

In testimony that I claim the foregoing as my own, I have hereto affixed my signature.

WILLIAM BLANCHARD.
